MORRIS HIRSHFIELD, OF NEW YORK, N. Y.

RESILIENT TREAD FOR SHOES.

1,296,802.

Specification of Letters Patent. Patented Mar. 11, 1919.

Application filed November 1, 1917. Serial No. 199,749.

To all whom it may concern:

Be it known that I, MORRIS HIRSHFIELD, a citizen of the United States, and resident of the city of New York, county of Kings, 5 and State of New York, have invented a certain new and useful Improvement in Resilient Treads for Shoes, of which the following is a specification.

My invention relates to resilient tread surfaces such as are commonly applied to the soles and heels of shoes and is characterized by a simple arrangement whereby the tread surface may be rapidly and conveniently attached and detached from a shoe and its shape 15 and contact with the shoe parts secured and maintained.

Heretofore resilient soles and heels have usually been secured to shoes by means of nails or possibly by stitching thus requiring 20 the services of a shoemaker not only for initially attaching but also for interchanging them from one shoe to another when they have worn down unevenly as is usually the case.

Difficulty has also been heretofore experienced in providing a tread member which would maintain its shape and lie in close contact with the bottom of the shoe as the nailing or stitching had to be placed some 30 distance in from the outer peripheral edge so as to allow for sufficient material to obtain a hold for the attaching means. The result was, particularly in the case of resilient soles, that the edges of the tread sagged 35 producing an unsightly appearance and permitting the entrance of dirt and water, causing a deterioration of the shoe sole, discomfort to the wearer and increased wear of the resilient tread.

40 The above disadvantages have been almost entirely overcome in the structure shown in the accompanying drawings forming part of my application, in which Figure 1 shows a bottom plan view of one example of my invention; Fig. 2 shows a section of Fig. 1 on the line 2—2; Fig. 3 shows a section of Fig. 1 on the line 3—3 and Fig. 4 shows a section of Fig. 2 on the line 4—4.

50 A resilient heel, and the same arrangement may be adapted to soles, is indicated in its entirety by the numeral 5 and comprises a lower member 6 and an upper member 7 which preferably are both comprised of resilient material with a plate 8 preferably 55 located between said members. The plate 8 has a crowned inner portion 9 provided with

screw holes 10 for securing the heel to the shoe. The plate 8 has a peripheral flange 11 provided with a plurality of openings 12, the purpose of which will more fully appear hereinafter. Instead of employing openings as 12 I may employ notches in the peripheral edge of said plate 8.

55 Screws 13 are adapted to pass through the holes 10 and press the crowned portion 9 and peripheral flange 11 toward the shoe to which the heel is secured as is readily apparent from the drawing.

In making my heel I cut two resilient members as 6 and 7 to the required shape, 70 and then place the plate 8 above referred to between the resilient members and vulcanize the heel thus formed. The openings 12 permit the resilient members 6 and 7 to form resilient bonds 14 through the plate 8 thus 75 integrally uniting the resilient members to each other. In case I employ notches as above referred to the bonds will be located on the periphery of the tread thus overcoming any possibility of the tread sagging 80 as hereinbefore described. It is often desirable to have the resilient members slightly larger in diameter than the steel plate. I therefore prefer to manufacture my heel with the said resilient members extending 85 beyond the peripheral edge of the metal plate. In this case the edges of the resilient members are also united in the vulcanization forming an integral unit which forms a substantial, easily attached and detached 90 heel when worn.

The lower member 6 may of course be provided with screw openings which register with the openings 10 of the plate 8 before the resilient members 6 and 7 are vulcanized 95 to each other, and in case I desire to provide such openings, which give a more finished appearance to the heel or sole, I provide such openings when the lower member is prepared, e. g. with a suitable die. The provision of a screw opening, however, is not necessary as it usually is possible to detect the position of the openings 10 by the slight circular depressions on the median line of the lower member after the members 6 and 105 7 have been vulcanized as above described. The finished heel may then be applied to each shoe by driving the screws 13 at the points indicated by the depressions above referred to. The lower resilient member 6 110 may be provided with suction disks such as well known in the art or any other suitable

devices to prevent non-slipping. I do not claim the disks shown but direct my claim to the structure above disclosed without limiting myself in any way to the specific features thereof.

It might be possible instead of providing a separate internally disposed member as 8 to form a tread of stratified resilient and rigid material; hence when I speak in my claim 10 of a member I do not mean that the member need necessarily be a separate and independent member and when I speak of openings in the plate I mean also to include notches.

When I speak in my claim of two resilient members united over a plate I also mean to include a single member which has been partially slit and the plate introduced therein.

As it is obvious that my improved tread 20 may be used upon the sole of the shoe or upon both the sole and heel as well as upon

the heel alone, I intend, when I use the word "heel" in the claim, that it shall include the word "sole" as well.

I claim:

A tread for shoes comprising a plate having a central recess and a peripheral flange outside of said recess and being provided with a series of openings located at spaced intervals on said flange and with apertures 30 in said recess for the accommodation of fastening devices, said plate being otherwise of unbroken continuity, and a heel of resilient material completely embedding said plate and fitting in surface contact with the opposite faces of said recess and said peripheral flange, said heel having a series of integral bonding portions extending through said series of openings transversely to said plate.

In testimony whereof I have hereunto set 40 my hand.

MORRIS HIRSHFIELD.
